UNITED STATES PATENT OFFICE

2,440,931

GRAINING MACHINE

Edward A. Casson, Washington, D. C.

Application January 3, 1944, Serial No. 516,897

1 Claim. (CL. 51—6)

1

The present invention comprises a graining machine for plates used in planographic processes, the graining being effected by an abrasive action administered when the plate carrying tub is reciprocated or subjected to a circulatory movement to constantly displace an abrasive, such as hydrated sand, superimposed on the plates, the abrasive being urged against the plates by suitable mobile bodies such as marbles. The object of the present invention is to provide a simple relatively inexpensive graining machine, operable to obtain all the benefits of machines heretofore used in the art, and available to the trade at only a fraction of the cost of said machines.

It is also within the contemplation of this invention to provide a plate holding tub operable in an eccentric circulatory path, the tub and its frame being spaced from and having no contact with the base or main frame of the machine, the tub and its frame being suspended over the base or main frame and operatively engaged with power means in the latter.

Other objects of the invention will be apparent from the following description of the present preferred form of the invention taken in connection with the accompanying drawings wherein:

Figure 1 is a perspective view of a machine constructed in accordance with the present invention;

Figure 2 is a vertical sectional view of the same;

Figure 3 is an elevational view of a modified form of the invention wherein the suspension means pends from a point above the graining tub; and

Figure 4 is a detail fragmentary sectional view of the tub and its frame, showing the interengaging means thereof.

The machine of the present invention includes a frame generally designated 5 which, in the form of invention illustrated in Figures 1 and 2 includes a cabinet in which the power means of the machine is mounted. The frame includes vertical standards or uprights 6, the lower ends of which are formed to provide, or are equipped with supporting feet 7, the upper ends of the stands or uprights being extended to provide, or are equipped with arms 8, the upper end of each of which is reversely turned to provide a hook 9, the terminal of which is provided with an aperture 10. It will be noted that the bills of the hooks overhang the top of the frame 5 as illustrated to advantage in Figures 1 and 2.

The frame in the present instance, is shown to be of rectangular configuration, although it is understood that any other contour may be used.

2

The frame includes suitable supporting shelves or bars 11, the lower of which, in the present embodiment of the invention, carries a motor 12 which is operatively engaged with a fly-wheel 13 for communicating power to a shaft 14. The motor is controlled in a manner well known in the art, by a switch 15 which is accessible from one side of the frame casing, by a button or the like 16. The shaft 14 extends upwardly through the top shelf or bar and the top of the frame. The shaft is mounted for rotation in bearing carrying housings 17 mounted on the shelves 11. Just above the upper of the housings 17 the shaft is offset, as indicated at 18, for a purpose more fully

hereinafter set forth.

Mounted for movement above the frame 5 is a plate carrying tub or box 19 in which the planographic or lithographic plates are adapted to be mounted for graining. As is well known in the

art, the plates have superimposed thereon, a hydrated sand which is worked over the surfaces of the plates by small mobile bodies such as marbles. The tub is hingedly mounted, as indicated at 20, on a frame 21, in a manner also well

known in the art. One end of the tub is equipped with handles 22 to facilitate elevation of said end of the tub for dispensing the contents of the latter. Dowels 23 may be mounted in the end of the tub below the handles 22 for engagement with

complemental openings formed in the frame 21 to prevent lateral displacement of the tub, independent of its frame 21, when the machine is in operation.

A bracket 24 extends from each corner of the frame 21 and is engageable with one end of an adjustable chain or other suitable flexible connection 25. The upper end of each chain is engaged in an aperture 10 of one of the supporting arms 8.

A bearing carried housing 17' is engaged with the bottom face of the frame 21 and depends from the latter through an opening 26 formed in the top of the frame 5. Upon reference to Figure 2 of the drawings, it will be observed that the housings 17 are in vertical alignment, located centrally in the frame 5, while the housing 17' is eccentric and engaged with the offset upper terminal 18 of the power shaft 14. Consequently, movement of the power shaft subjects the tub to an eccentric

circulatory movement.

The frame or cabinet 5 may be provided with a marble carrying drawer 27, preferably arranged immediately below the top of the frame or cabinet. The drawer is accessible from the outside of the cabinet and is also in communication with

the recessed top 28 of the frame or cabinet through an apertured collar 29 in said top.

In the modified form of invention illustrated in Figure 3, I prefer to suspend the tub from a ceiling or other overhanging support 31. In this form of invention, the tub 19' is supported at its corners by adjustable and flexible supporting elements 25', the upper end of each of which is engaged with an eye 30 carried by said support 31. The lower end of each of the supporting elements 25' is engaged with the tub and its frame in the same manner as shown in the form of invention illustrated in Figures 1 and 2. In this form, the frame or cabinet 5, if desired, may be eliminated and a suitable supporting means 11' only employed, through which a power shaft 14' extends for operative engagement with the tub and its frame in an obvious manner. The power shaft 14' is connected to a suitable source of energy.

With the present invention, rotation of the shaft 14 or 14' imparts movement to the tub or box 19 or 19'. This imparts an eccentric circulatory motion to the tub which is predetermined. In both forms of the invention herein illustrated, the tub and its frame is completely free from contact with the main frame or other supporting base which may be employed. On the contrary, the tub is suspended above and appreciably spaced from the top of the main frame or other means supporting the power shaft. This results in a complete absence of friction between the tub and the main frame, and further insures a smoother and more effective operation in the displacement

of the mobile mass superimposed on the plates in the tub. As is apparent, the suspension means or chains 25 and 25' are susceptible of adjustment for obvious reasons.

5 Although I have herein described preferred forms of my invention, it is nevertheless to be understood that various changes may be made therein, within the scope of the claim hereto appended.

10 What I claim is:

15 A graining machine comprising a frame having a closed recessed top provided with an apertured collar, a drawer mounted in the frame directly below the said collar to receive materials deposited on said top, a tub assembly suspended by the frame, above and in spaced relation to the closed top of the latter, one end of the tub being hinged to permit tilting of the latter, on its assembly, for dispensing materials, carried by the tub, onto the recessed top of the frame.

20 EDWARD A. CASSON.
